CLAIM

The ornamental design for a cigarette paper dispenser, as shown and described.

DESCRIPTION

FIG. 1 is a perspective view of a cigarette paper dispenser, showing our new design;

FIG. 2 is a front elevational view, the rear elevation
being identical thereto;

FIG. 3 is a mouth end elevational view thereof;

FIG. 4 is a side elevational view thereof;

FIG. 5 is an elevational view of the end opposite that shown in FIG. 3.

FIG. 1.

FIG. 2.

FIG. 3.

FIG. 4.

FIG. 5
